(57) **CLAIM**

The ornamental design for a spool dispenser, as shown and described.

DESCRIPTION

FIG. 1 is a perspective view of a horizontally mounted embodiment of a spool dispenser showing our new design.

FIG. 2 is a left side elevation view thereof.

FIG. 3 is a right side elevation view thereof.

FIG. 4 is back elevation view thereof.

FIG. 5 is a front elevation view thereof.

FIG. 6 is a top plan view thereof.

FIG. 7 is a bottom plan view thereof; and,

FIG. 8 is a perspective view thereof with the broken-line disclosure of a spool being for illustrative purposes only and forming no part of the claimed design.

The broken-lines are for illustration purposes only and form no part of the claimed design.
